UNITED STATES PATENT OFFICE.

AUGUST LEOPOLD SCHAAR, OF CHICAGO, ILLINOIS, ASSIGNOR OF ONE-HALF
TO THE ROOT & SONS MUSIC COMPANY, OF SAME PLACE.

ACCORDION.

SPECIFICATION forming part of Letters Patent No. 295,288, dated March 18, 1884.

Application filed September 27, 1883. (No model.) Patented in Germany May 6, 1882, No. 21,611.

To all whom it may concern:

Be it known that I, AUGUST LEOPOLD SCHAAR, a citizen of the United States of America, residing in Chicago, in the county 5 of Cook and State of Illinois, have invented certain new and useful Improvements in Accordions and Analogous Keyed Musical Instruments, of which the following, in connection with the accompanying drawings, is a specification.

In the drawings, Figure 1 is a top view of an accordion embodying my invention. Fig. 2 is a bottom view of the same, and Fig. 3 is a central cross-section thereof.

Like letters of reference indicate like parts. My invention relates chiefly to the means employed for rendering the keys or finger-levers yielding. It also consists in certain other features of construction, all of which 20 will be hereinafter fully described, and the essential features of my invention will be particularly set forth in my claims.

A represents the top piece, below which are arranged the reeds and the bellows or extensible and compressible air-chamber and its supplemental keys and valves. As my invention relates chiefly to the means employed for rendering the valves and their levers yielding, I have only shown with particularity the parts 25 appertaining to and immediately in connection with and including the said means.

B B are the valve-openings, and C C are the valves.

D is the key-board, and E E are the keys. The keys are arranged in recesses F F in the key-board, and are supported on a rod or wire, G, passing through them and longitudinally through the key-board. In other words, the keys which, mechanically considered, are levers, are fulcrumed on the rod or wire G, which is removable.

H H are wires or arms connecting the valves C C to the keys E E.

The features of construction thus far described have heretofore been commonly employed, and the usual way of rendering the keys yielding has been by separate springs behind each key in the recess of the key-board.

The arms H H are connected rigidly to the 50 keys E E, and the said arms and keys constitute rigid angle-levers for operating the valves.

To render the keys yielding, I extend the wires or arms H H entirely through the levers of the keys, and make these arms long enough to permit their free ends to rest upon springs, to 55 which I will hereinafter refer. These rearward-extending arms are shown at a a, Figs. 1 and 3. The top piece, A, has upon it a molding or frame, A', and I I are springs attached to the said molding or frame, and extending 60 underneath the rear or free ends of the arms or wires H H; but these springs may also be attached directly to the top piece, A, being formed to allow their free ends to yield under the pressure exerted upon the keys while the 65 instrument is being played, as will hereinafter more fully appear. The molding or frame A', however, not only gives a finished appearance to the instrument, but also serves to support the keys somewhat above the part A, so that 70 their free ends may yield sufficiently for the purpose for which they are intended. The springs I I have sufficient force to hold the valves C C down yieldingly upon the valve-openings. By this means the valves may be 75 raised in the usual manner, and they will be closed automatically by means of the springs I I when the pressure is removed from the keys.

It will be perceived from the foregoing description and from reference to the drawings that the springs I I are located where they are much more accessible than if they were arranged in the board D and behind the keys E E, as heretofore. They may also be applied 80 and removed or repaired with greater facility, and less expense is involved in their construction and application.

The air-valve and base or supplemental keys may also be combined with springs I I in the 85 manner already described, and as indicated in Figs. 2 and 3.

It is obvious that these improvements may be employed with advantage to similar instruments—for instance, such as concertinas.

Having thus described my invention, what I claim as new, and desire to secure by Letters Patent, is—

1. The combination, substantially as specified, of the valves, the keys E E, the arms 90 H H, connected rigidly to the said keys, and also connected to the valves, and the external

springs, I I, all arranged substantially as shown and described with relation to each other and the key-board, for the purposes set forth.

- 5 2. The combination of the valves C C, rigid angle-levers E H, connected to the valves, the parts H H passing through the parts E E and forming extensions *a a* upon the keys, the springs I I, bearing on the said extensions, and 10 the key-board, substantially as and for the purposes set forth.
3. The combination of the top piece, A, the frame or molding A', the key-board D, valves

C C, arms H H, keys E E, and springs I I, the said keys and arms forming rigid angle-levers 15 connected to the valves, and the said springs being arranged horizontally outside of the key-board and bearing on the said levers, substantially as and for the purposes specified.

In testimony that I claim the foregoing as 20 my own, I have affixed my signature in presence of two witnesses.

AUGUST LEOPOLD SCHAAR.
